UNITED STATES PATENT OFFICE.

JAMES D. McDONALD, OF LYNN, MASSACHUSETTS, ASSIGNOR TO GENERAL ELECTRIC COMPANY, A CORPORATION OF NEW YORK.

PROJECTOR

1,267,881.

Specification of Letters Patent.

Patented May 28, 1918.

Application filed December 1, 1916. Serial No. 134,313.

To all whom it may concern:

Be it known that I, JAMES D. McDONALD, a citizen of the United States, residing at Lynn, in the county of Essex, State of Massachusetts, have invented new and useful Improvements in Projectors, of which the following is a specification.

My invention relates to a headlight and more particularly to a mechanism for adjusting the position of the lamp.

Headlights are commonly provided with a reflector especially of the parabolic type, located back of the light source, so as to throw the beam of light forward. It is, of course, important that the light source should, as nearly as possible, be made to coincide with the focus of the reflector, since any displacement therefrom, such as is likely to result from shocks incident to the movement of the vehicle or from faulty construction of the lamp itself, disturbs the parallelism of the rays constituting the reflected beam.

My invention provides a ready and convenient means for adjusting the position of the lamp from without the casing so that the same may readily be brought into the focus of the reflector.

Other novel features of my invention will appear from the specification, and will be particularly pointed out in the claims.

For an understanding of my invention, reference may be had to the accompanying drawings, in which: Figure 1 is a side view 35 partially in section of a headlight embodying my invention; Fig. 2 is a section on the line 2—2 of Fig. 1, looking in the direction of the arrows; Fig. 3 is a detail view; Fig. 4 is a view similar to Fig. 1 showing 40 a modified form of my invention; Fig. 5 is a cross section on the line 5—5 of Fig. 4; and Fig. 6 is a detail view of certain parts shown in Fig. 4.

Referring now to the drawings, and first 45 to Figs. 1, 2 and 3, 10 is a headlight casing closed at the back at 10^a and provided at the front with a door 11 which is hinged at 12. The reflector which may be of any usual form, is indicated by the numeral 13. The bulb of an incandescent lamp 14 is located within the reflector in such a position that the filament of the lamp may be made to coincide with the focus of the reflector. The lamp socket extends rearwardly through an opening 18^a in the cen-

ter of the reflector, and is mounted in a support which affords the lamp a universal movement. This support may be the same as that shown in a Patent #1,196,506, which was issued to Percy S. Bailey, on August 29, 1916, and to which reference may be made for details further than those here described. This supporting means comprises what is essentially a ball and socket joint, the ball 16 being provided with a central opening through which the socket of the lamp passes. Because of the fact that the lamp is so mounted with reference to the reflector that but a slight movement of the same is ever necessary to bring the same into focus, I have shown the ball as consisting of only a small section of a sphere. The member 16 is split as shown in Fig. 2, and is preferably provided with a U-shaped section 17 which is somewhat elastic and is so biased as to open the ball away from the lamp socket when pressure on the same is released. The ball 16 is surrounded by a socket 18 somewhat thicker than the member 16, and which preferably comprises two members 18^a and 18^b pivoted together at 19. One member 18^b of the socket is preferably stationary and is secured by screws 20 on bosses (not shown) on a plate 21 which is secured by screws 22 to the rear portion 10^a of the casing. The two sections of the socket 18 are clamped about the ball or released by a member 23 (see Fig. 2) which extends through the casing and which is provided toward the inner end with a collar 24 secured to the rod 23 by a pin 25, and which engages a boss on the section 18^a of the socket. The inner end of the rod 23 is screw-threaded and engages a corresponding screw-threaded opening of the member 18^b of the socket. The outer end of the rod 23 is provided with a suitable handle 26 for rotating the member 23, so that the socket 18 may be brought into clamping engagement with the ball 16 or released from engagement therewith.

Now, in order to impart to the lamp a universal movement about its support, I provide a member A comprising a spanner 27 (see Fig. 3) pivoted to the socket of the lamp at 28. The member A also comprises a rod or bar 29 secured to the spanner and passing through an opening 30 in the lower side of the casing which acts as a pivot for the member, and a rod or bar 31 also secured

to the spanner on the upper side and passing through an enlarged opening 32 in the upper side of the casing. This opening is covered by a cap 33 which is secured to the upper end 5 of the bar 31 and constitutes a hand-piece by which the member A may be moved either laterally in any desired direction about the point where the lower end passes through the casing as a pivot in order to effect a lateral 10 or axial displacement of the lamp filament or longitudinally to effect a corresponding vertical movement of the lamp. I am thus enabled to impart a universal movement of the lamp about its support. The opening 32 in the upper side of the casing is surrounded by an annular ring 34 on which a disk 35 is seated, a spring 36 being interposed between the cap 33 and the disk 35. To adjust the position of the lamp it is only necessary first to release the socket 18 from its clamping position about the ball 16 by turning the handle 26. Then by moving the handle 33 either laterally or longitudinally, the lamp may be moved about its support in any desired direction and brought within the focus of the reflector.

In Figs. 4, 5 and 6 I have shown my invention embodied in a headlight of a somewhat different type. The form of casing 30 shown in Fig. 1 is that usually employed with a headlight that is mounted on the front of the dashboard of a car, while the headlight shown in Figs. 4, 5 and 6 is provided at the rear with a contracted portion 35 which is intended to project through an opening in the dashboard. In the form here shown, the socket of the lamp is not engaged by a ball and socket support, but the rear end of the socket is engaged by suitable 40 springs preferably three in number, mounted on the rear of the casing and extending forwardly but tapering toward the axis of the headlight. The springs as stated, engage the rear end of the socket of the lamp and afford a universal movement therefor. Because of the limited amount of space within the casing of a lamp of this type, I have shown a member for imparting to the lamp a universal movement about this support but 45 which differs therefrom in certain details, although it is the same in principle as that shown in Fig. 1. In the form of headlight here shown, the spanner of the member A is located within the contracted portion of the casing at the rear, and it is therefore necessary to bend the rods 29^a and 31^a around the reflector. The rod 31^a passes through an opening in the wall of a cup secured to the inner wall of the casing 10 and on the upper

side thereof. The lower end of the rod 29^a 60 passes through a bushing B comprising a section 39 formed with a flange 39^a located within the casing and around an enlarged opening 32. Another section 40 is located without the casing, the two pieces being held together by an externally screw-threaded member 43 engaged at its lower end by an internally screw-threaded sleeve 42. The upper end of the member 43 is provided with an enlarged saw cut, tapering head 43 engaging a corresponding tapering opening in the section 39. The lower end of the rod 29^a is provided with a suitable operating handle, 45.

In order to adjust the position of the lamp shown in Figs. 4, 5, and 6, the parts of the bushing B are unclamped by unscrewing the sleeve 42 when the bushing may be moved laterally or in vertical plane to any desired position and clamped in the adjusted position, by again screwing home the sleeve 42. 70 It will be understood, of course, that the rod 29^a may be moved longitudinally the same as that shown in the previous figures.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. A headlight comprising a casing, a reflector located therein, an incandescent lamp located within the reflector, a support for the lamp affording the same a universal movement, and a member engaging the lamp socket, one end of said member being pivoted in the casing and the other end passing through and laterally movable in the opposite side of the casing whereby the position of said lamp may be adjusted with reference to the reflector from without the casing. 95

2. A headlight comprising a casing, a reflector, located therein, an incandescent lamp located within the reflector, a support for the lamp affording the same a universal movement, and a member engaging the lamp socket, one end of said member being pivoted in the casing and the other end passing through and laterally movable in the opposite side of the casing, and means for securing the lamp in its adjusted position. 100 105

In witness whereof, I have hereunto set my hand, this 28th day of November, 1916.

JAMES D. McDONALD.
